UNITED STATES PATENT OFFICE.

DAVID S. SPECTOR, OF NEW YORK, N. Y., ASSIGNOR TO FEDERAL TELEGRAPH COMPANY, OF SAN FRANCISCO, CALIFORNIA, A CORPORATION OF CALIFORNIA.

DESIGN FOR A RADIOCABINET.

Application filed November 13, 1926. Serial No. 19,704. Term of patent 14 years.

To all whom it may concern:

Be it known that I, DAVID S. SPECTOR, a citizen of the United States of America, residing at New York city, in the county and State of New York, have invented a new, original, and ornamental Design for a Radiocabinet, of which the following is a specification, reference being had to the accompanying drawings, forming part thereof.

Figure 1 is a front view of the radio cabinet; and Fig. 2 is an end view of the radio cabinet showing my design.

I claim:

The ornamental design for a radiocabinet as shown.

DAVID S. SPECTOR.
